LASTING MACHINE

Harold Lane and John William Pratt, Leicester, England, assignors to United Shoe Machinery Corporation, Paterson, N. J., a corporation of New Jersey

Application January 31, 1936, Serial No. 61,794
In Great Britain March 16, 1935

7 Claims. (Cl. 12—14)

This invention relates to lasting machines, and is herein illustrated as applied to a machine of the character disclosed in United States Letters Patent No. 1,949,539, granted on March 6, 5 1934 upon an application of Joseph Gouldbourn, Fred Ricks and William T. B. Roberts for lasting the heel ends of shoes. It is to be understood, however, that the invention is not limited to machines of that particular character or to heel-10 end-lasting machines.

The machine disclosed in the above-mentioned Letters Patent is capable of operating upon shoes of widely different sizes, and for this purpose not only is it provided with means for adjustably 15 varying the limit of movement of the heel-lasting wipers, but the wipers themselves have detachable forward end portions which may be removed in operating on shoes of very small sizes. The wipers, including these detachable end portions, are provided, moreover, with means for driving fastenings from them into the shoe bottom to fasten the upper in lasted position. The wiping edges of the end portions of the 20 wipers may be curved inwardly lengthwise of the shoe at their forward ends, so that in the wiping operation they tend to draw the margin of the upper rearwardly and thus prevent it from being pushed forwardly and bulged upwardly in front of the wipers. If the wiping edges are 25 curved in this manner, there may be danger under some conditions that the end portions of the wipers at the opposite sides of the shoe will engage each other before the wipers complete their wiping movements, with resulting damage to the 30 machine.

An object of the present invention, among others, is to avoid such danger of damage to a machine in the operation of end-lasting wipers. The invention accordingly provides wipers of 40 novel construction having at their forward ends wiping members which are yieldable laterally of the shoe relatively to other portions of the wipers. In the construction herein shown such laterally 45 yieldable end-wiping members are supported on other end-wiping members which are yieldable heightwise of the shoe as and for the purpose disclosed in the previously mentioned Letters Patent, and the laterally yieldable members are further yieldable heightwise of the shoe with these 50 other members. The use of such laterally yieldable members in a machine of the character disclosed, for example, in the above-mentioned Letters Patent permits the detachable end portions of the wipers to be left in place in operating on 55 very small shoes in case it is desired to drive

more fastenings than are provided for by the main portions of the wipers, and in any event serves to insure against damage to the machine if the operator fails to remove the detachable end portions when the wipers are adjusted for 5 very small shoes.

The above and other features of the invention, including various novel details of construction and combination of parts, will now be more particularly described by reference to the accompanying drawings and pointed out in the claims.

In the drawings,

Fig. 1 is an inverted plan view of one form of wipers constructed in accordance with the present invention with the wipers shown in fully retracted relation to a shoe indicated by dot-and-dash lines;

Fig. 2 is a view similar to Fig. 1, but showing the wipers in fully closed relation to the shoe;

Fig. 3 shows in elevation a portion of one of the wipers as viewed in the direction of the arrow 3 on Fig. 1;

Fig. 4 shows the same portion of the structure as Fig. 3, as viewed in the direction of the arrow 4 on Fig. 1;

Fig. 5 is a perspective view showing in disassembled relation parts of the structure shown in Figs. 3 and 4;

Fig. 6 is a perspective view of a modified form of end wiper device;

Fig. 7 is a perspective view of a modified form of end piece associated with the device shown in Fig. 6;

Fig. 8 shows in perspective the end wiper device of Fig. 6 with parts thereof in disassembled relation and inverted relatively to the parts shown in Fig. 6;

Fig. 9 is an elevation, partly in section, showing the modified end wiper device and associated parts viewed in the same direction as are the parts shown in Fig. 3; and

Fig. 10 shows partly in elevation and partly in section the same structure as Fig. 9, viewed in the same direction as are the parts shown in Fig. 4.

The form of wipers shown in Figs. 1 to 5, inclusive, comprises wiper blocks 1 and 3 similar to the blocks 33 shown in the previously mentioned Letters Patent, these blocks having detachably secured to their forward ends, by screws 50 5 and dowel pins 7, end pieces 9. These end pieces carry wiping members 11 provided with upwardly extending stems 13 slidably mounted in the end pieces, the members 11 being pressed down toward the shoe bottom by springs 15 55

Fig. 4) in the end pieces. Downward movement of the stem 13 is limited by pins 17 extending through the stems and engaging the end pieces. The wiping members 11 can thus yield upwardly in the same manner and for the same purpose as the members 63, 68 shown in the above-mentioned Letters Patent. The end pieces 9 and the wiping members 11 have in them driver passages 19 and spring-pressed balls 21 which retain tacks fed down passages in the end pieces into the driver passages, as also disclosed in the prior Letters Patent.

For purposes of this invention each wiping member 11 has secured to it a block 25 having a projection 27 (Fig. 5) which enters a recess 29 in the member 11. A screw 31 extending through a hole 33 in the member 11 and threaded in the block 25 holds the block in place. Each wiping member 11 has formed in it a vertical bore 35 in which is rotatably mounted a stem 37 extending from another wiping member 39. The member 39 and the block 25 have in them cylindrical recesses 41, 43 (Fig. 1) which receive a spring 45 normally holding a face 47 on the member 39 against a stop face 49 on the member 11. Each member 39 has a wiping face 51 (Fig. 5) provided with a rounded work-engaging edge 53 which, when the faces 47, 49 are in engagement with each other, forms a continuation of a rounded work-engaging edge 55 (Fig. 1) on the wiping member 11. It will be seen that the edges 53 are also curved inwardly widthwise of the shoe in directions toward the toe end of the shoe. Each wiping member 39 has a lip 57 which engages the upper face 59 (Fig. 4) of the wiping member 11 to prevent the member 39 from dropping away from the member 11 and to maintain the work-engaging faces of the two members in the same horizontal plane. It will be evident that the two members are yieldable upwardly together against the resistance of the spring 45 in the wiping operation. Outward yield of each member 39 against the resistance of the spring 45 is limited by engagement of a lug 61 on the block 25 with the bottom of a recess 63 in the member 39. The springs 45 are strong enough to prevent the members 39 from yielding in wiping over the margin of the upper.

The modified construction shown in Figs. 6 to 10, inclusive, is associated with wiper blocks similar to those shown at 1 and 3 in Fig. 1. Each of these wiper blocks has secured to it by a screw and a dowel pin an end piece 70, and each end piece has slidably mounted in it a stem 72 extending vertically from a wiping member 74 which is pressed downwardly by a spring 76 in the end piece. Downward movement of each member 74 is limited by a pin 78 extending through the stem 72 and engaging the end piece 70. The wiping members 74 can thus yield upwardly in the same manner as the members 11 of the first-described construction. Each end piece 70 and member 74 are provided with driver passages 80 and also with tack-retaining means as in the first construction. Each member 74 has formed integral with it a block 82 similar in shape to the detachable block 25 of the first construction, and has within it a vertical bore 84 to receive a vertical stem 86 extending from a wiping member 88. Each member 88 has therein a recess which receives one end of a spring 90 the other end of which lies in a recess in the block 82. The spring 90 normally holds a face 92 on the wiping member 88 against a stop face 94 on the wiping member 74. The bore in the block 82 is

so formed that the spring 90 may be inserted after the wiping member 88 has been assembled with the member 74, and a pin 95 (Fig. 9) is provided in the block 82 for one end of the spring to abut against. Each wiping member 88 has a wiping face 96 provided with a rounded work-engaging edge 98 which, when the faces 92 and 94 are held in engagement with each other by the spring 90, forms a continuation of a rounded work-engaging edge 100 on the wiping member 74. The edge 98 is also inwardly curved similarly to the edge 53 in the first-described construction. The wiping member 88 is prevented from moving downward relatively to the wiping member 74 by a plate 102 which has in it a dovetailed guide 104 for engagement with a dovetailed guide 106 on the wiping member 88. The plate 102 is secured to the wiping member 88, after the latter has been assembled with the member 74, by a screw 108 inserted through a hole 110 in the plate and into a threaded hole 112 in the member 88. A face 113 (Fig. 10) on the plate 102 and a face 114 on the member 88 engage respectively upper and lower faces on a projecting portion 116 of the member 74, and while permitting the member 88 to swing about the axis of the stem 86 prevent upward and downward movements of the member 88 relatively to the member 74. It will thus be seen that in the modified construction the wiping member 74 and the block 82 are formed as a single part, instead of as two parts, and that there are two parts 88 and 102 instead of a single part.

From the foregoing description it will be readily understood that if, for operation on a shoe of small size into which it is desired to drive more tacks than the wiper blocks 1 and 3 provide for, these blocks and with them the end pieces 9 or 10 have been so adjusted that in the wiping operation the wiping members 39 or 88 come into contact with each other, these members will yield against the resistance of the springs 45 or 90 and no damage to the machine will result. Likewise no damage will result if the operator should omit to remove the end pieces in operating upon a shoe of small size into which are to be driven only the number of tacks provided for by the wiper blocks 1 and 3.

The laterally yieldable wiping members 39 or 88 have been described as applied to end pieces each provided with two tack driver passages and with an upwardly yieldable wiping member 11 or 74, but it should be understood that such laterally yieldable wiping members may be used in conjunction with end pieces each having only one driver passage, or with end pieces which do not have upwardly yieldable wiping members. It is also to be understood that such laterally yieldable wiping members may be used in a construction where there are no detachable end pieces.

Having described the invention, what we claim as new and desire to secure by Letters Patent of the United States is:

1. In a lasting machine, end-lasting wipers movable inwardly toward each other around an end of a shoe, said wipers having at their forward ends wiping members yieldable laterally of the shoe relatively to other wiping portions of the wipers to permit said members to engage each other without damage to the machine in the wiping operation.

2. In a lasting machine, end-lasting wipers movable inwardly toward each other around an end of a shoe, said wipers having at their for-

ward ends wiping members mounted for swinging movements laterally of the shoe relatively to other wiping portions of the wipers, and springs arranged to control said members and yieldable upon engagement of the members with each other in the wiping operation.

5. In a lasting machine, end-lasting wipers movable inwardly toward each other around an end of a shoe, said wipers having at their forward end portions wiping members yieldable heightwise of the shoe relatively to other wiping portions of the wipers in the wiping operation, and other wiping members yieldable heightwise of the shoe with said first-named members and also yieldable laterally of the shoe to permit them to engage each other without damage to the machine in the wiping operation.

6. In a lasting machine, end-lasting wipers movable inwardly toward each other around an end of a shoe, said wipers having at their forward end portions wiping members yieldable heightwise of the shoe relatively to other wiping portions of the wipers in the wiping operation, other wiping members yieldable heightwise of the shoe 25 with said first-named members and pivotally mounted on the latter for swinging movements laterally of the shoe, and springs arranged to control said other members and yieldable upon engagement of said other members with each 30 other in the wiping operation.

5. In a lasting machine, end-lasting wipers movable inwardly toward each other around an end of a shoe, said wipers having detachable end portions including wiping members yieldable laterally of the shoe relatively to other wiping portions of the wipers to permit said members to engage each other without damage to the machine in the wiping operation.

6. In a lasting machine, end-lasting wipers movable inwardly toward each other around an end of a shoe, said wipers having detachable end pieces at their forward ends, wiping members carried by said detachable end pieces and yieldable heightwise of the shoe relatively to said end pieces in the wiping operation, and other 15 wiping members also carried by said detachable end pieces and yieldable laterally of the shoe relatively to the end pieces to permit said other members to engage each other without damage to the machine in the wiping operation. 20

7. In a lasting machine, end-lasting wipers movable inwardly toward each other around an end of a shoe, each of said wipers having at its forward end a pair of wiping members both yieldable heightwise of the shoe relatively to other 25 wiping portions of the wiper and one yieldable relatively to the other laterally of the shoe.

HAROLD LANE. JOHN WILLIAM PRATT. 30
